WALKING TOY

Application filed March 21, 1930. Serial No. 437,707.

The object of the present invention is to produce a walking toy which will closely simulate the movements of a person when walking. In accomplishing this object, the toy figure is formed with a body member carrying a motor-driven oscillating weight, two leg members independently swivelled upon the body member to allow restricted freedom of motion relatively in horizontal and vertical planes, and foot members swivelled upon the leg members for horizontal movement thereon and connected through suitable springs to yieldingly hold the feet in normal position upon the legs and at the same time permit slight swivelling and forward swaying movements of the legs upon the feet in the walking operation. Each leg member is swivelled at its upper end to the body member and carries a projection which extends through a slot formed in the body member, suitable spring stops upon the body member engaging said leg projections and permitting slight relative movements between the legs and the body member in both vertical and horizontal planes. Said leg projections are preferably formed with cams which act upon the body portion to assist the slight relative backward turning movements of the body upon the legs, induced by the oscillating weight to simulate the slight backward turning or swinging motion of the body and the throwing forward of the legs as in the natural act of walking.

To operate the walking toy the clock-work motor mounted upon the body member actuates a rotating wing or paddle that alternately engages opposite pallets upon a rocking member that carries upon a spring arm an adjustable weight which is presented in position above the center of gravity of the figure to properly balance the figure on the feet and, when actuated by the clock mechanism, to oscillate from side to side and impart to the body slight jolting impacts upon opposite sides of the center of gravity, to cause the balanced figure to sway first one way and then

the other, alternately upon the right foot member and the left foot member, causing the foot members to be lifted and moved slightly forward one after the other in a manner similar to the natural action of a person walking. 50

In order that the invention may be fully understood, it will first be described with reference to the accompanying drawings and the novelty afterwards more particularly pointed out in the annexed claims. 55

In said drawings Figure 1 is a front elevation of the improved walking toy mechanism, showing in dotted lines a fanciful figure of a man that can be employed to conceal the mechanism. 60

Figure 2 is a side elevation of said mechanism. 65

Figure 3 is a rear elevation of the same showing the body member in vertical section and the leg members partly broken away. 70

Figure 4 is a top plan view of the mechanism. 75

Figure 5 is a horizontal sectional view taken on the line 5—5 of Figure 3. 80

Figure 6 is a detail vertical sectional view taken on the line 6—6 of Figure 3. 85

Figure 7 is a horizontal sectional view taken on the line 7—7 of Figure 2. 90

The improved walking toy comprises a body member carrying a motor-driven actuating weight, leg members having swivel connection with the body member and foot members swivelled upon the leg members, the whole being so proportioned and arranged to stand erect in balanced position upon the foot members and caused by the action of the rocking weight to simulate the action of a person when walking. 95

The body member, as illustrated in the accompanying drawings, consists of a substantially cylindrical hollow box 1 preferably formed of sheet metal and having the top wall 2 and the bottom wall 3. Rigidly mounted upon top wall 2 of body member 1 and projecting upwardly therefrom is a 100

clock-work frame 4 containing a train of gears indicated at 5 driven by a spring 7 having a winding arbor engaged by a key 8 projecting rearwardly from the walking figure. 5 This spring operated train of gears may be any well-known clock-work mechanism such as is commonly employed in operating mechanical toys.

The arbor 9 of the clock-work mechanism 10 projects forwardly through the supporting frame 4 and has mounted upon it a rotary wing or paddle 10 which alternately engages the pallets 11 projecting inwardly from one bar 12 of a laterally oscillating U-shaped 15 frame. The bar 12 is journaled at 13 upon the top plate 2 of body member 1 to present the pallets 11 in opposite relation, above and below, the rotary wing or paddle 10, so that in the rotation of the wing or paddle 10 said 20 U-shaped frame will be oscillated from side to side upon the body member.

The bar 12 is connected at top through the cross-bar 14 with the second bar 15 of said U-shaped oscillating frame, the bar 15 being 25 journaled at 16 upon the top plate 2 in rear of the clock-work mechanism, it being clear that the oscillating U-shaped frame projects upwardly from body member 1 and straddles the clock-work mechanism. The bar 15 30 of the oscillating U-shaped frame is formed between its ends with a slotted yoke 17, through the slot of which projects the winding arbor or the barrel of the operating key 8, the slot permitting the free oscillation of 35 the upstanding U-shaped frame 12, 14, 15.

Projecting upwardly from the bar 15 is a bracket 18 supporting at one end a forwardly and horizontally presented spring blade or arm 19 having a longitudinal slot 40 20 and upon which is adjustably mounted a weight shown in two sections 21 secured together by a screw bolt 22 passed through the slot 20 and clamping the two sections of the weight in the desired adjusted position upon 45 the spring blade or arm 19. The spring blade or arm 19 rests between two limiting spring blades 23 projecting from the bracket arm 18, the purpose of said blades 23 being to slightly 50 stiffen the blade or arm 19 and confine the point of flexure of the spring blade or arm 19 approximately to the vertical transverse plane through the center of gravity of the walking toy.

The lower end of bar 15 of the oscillating 55 weight carrying frame is formed with impact shoulders 24 projecting oppositely from the pivot 16 in position to engage the face of the body top 2, thereby limiting the oscillating strokes of the weight-carrying frame and imparting a slight jolting blow to the body member at the completion of each rocking movement of the weight-carrying frame, said blows being delivered first on one side 60 and then on the other side of the center of

gravity of the body member to effect the alternate swaying of the figure.

Said oscillating frame is also provided upon the lower end of bar 15 beneath pivot 16 with an angular detent 25 which is engaged by a triangular spring pressed detent 26 extending through a slot in the body top plate 2, said detent 26 being formed on an arm 27 secured to the underface of top plate 2 by means of a screw or rivet 28. An expansion spring 29 engages the lower face of detent arm 27 and is confined by its engagement with the body bottom plate 3, said spring 29 yielding holding the detent 26 in engagement with the detent 25 of the weight carrying 75 rocking frame. Each movement of the rocking frame forces detent 26 downwardly by the cam action of detent 25 thereon, the spring 29 yielding to allow detent 25 to pass and immediately causing detent 26 to move upwardly into engagement with the opposite face of detent 25. The action of this spring pressed detent 26 is to assist the weight in producing positive jolting blows to the body by the action of the oscillating weight-carrying frame. 80

It will be observed that the weight is mounted upon a spring blade or arm supported from the rear bar of the oscillating frame and extending forwardly horizontally 95 across the vertical transverse plane that extends through the center of gravity of the body, the movement of the weight from side to side tending to sway the body to and fro, and the resiliency of the spring arm permitting the weight to swing or snap slightly to the rear at the completion of each impact of the oscillating frame. 100

The body and motor-driven weight are supported in balanced position upon two 105 legs indicated at 30 and 31. These legs may be made of any suitable material and shape and as shown in the drawings, are formed of properly shaped sheet metal tubes having top plates 32 and bottom plates 33. Near the forward edge of each leg top plate 32 is secured one leaf of a horizontal hinge 34, the other leaf of said hinge carrying a vertical pivot pin 35 which passes freely through a vertical socket 36 carried by the bottom plate 3 of body member 1. This vertical pivot 35 passes up through an opening in the body bottom plate 3 and receives a cross pin 37 which rests upon a wear washer 38 and completes the jointing of the leg member with the body member, said described joint permitting relative movement between each leg member and the body member upon both the horizontal hinge and the vertical pivot pin. 110 This joint between the body member and the leg member forward of the center of gravity of the leg member will permit each leg member to gravitate forwardly upon its joint when the leg is lifted by the swaying of the body, and said joint will also permit a slight turn- 115 120 125 130

ing of the body member upon the leg upon which the body is fulcrumed and swayed. To restrict such movements between body and leg members, each leg member carries near the rear edge of top leg plate 32 an upwardly projecting arm 39 which extends through a slot 40 of body bottom plate 3, said arm being notched at 41 to receive a spring wire 42 which is supported at its forward end within body 1 upon a hinge 43, the arrangement being such that the spring wire 42 presses inwardly against the notched arm 39 to yieldingly hold it in engagement with the inner edge of the slot 40. The spring wire 42 projects across the slot 40 and, depending upon the notch of arm 39 that it engages, will to that extent limit the relative movement between the body 1 and rear of the leg 30 or 31, as the leg gravitates forwardly in taking a step.

These arms 39 projecting from leg members into the body member are formed with cam edges 44 which are designed to engage the inner edges of the slots 40 to assist the slight rearward turning movements of the body member upon the vertical leg pivots 35 when the swinging weight sways the body member laterally and rearwardly upon a leg acting as a fulcrum.

The leg members 30 and 31 are supported upon foot members which are connected to the leg members by pivot joints. Each foot member 45 is mounted upon a pivot rod 46 which extends up through the bottom leg plate 33 and the intermediate partition plate 47, said rod 46 being rigidly attached to the foot member and journaled in plates 33 and 47. The bottom leg plate 33 has a bearing opening through it which fits loosely upon the enlarged bearing hub portion 48 of the rod 46 so as to allow relative axial motion between the leg member and its supporting foot member. Each foot also carries a lug 49 which engages an inclined notch 50 in the lower end of the leg member, to restrict the relative movements between the leg members and the foot members. Each rod 46 has coiled upon it a spring 51 having one end attached to the rod and the other end attached to the partition wall 47, the purpose of said spring being to hold the swivel foot 45 in normal position upon the leg, while permitting the relative axial movement between these parts at the proper times.

The walking toy mechanism may be enclosed in any desired form of figure, such as indicated by dotted lines in Figure 1 of the drawings, in which the form of a man is drawn around the mechanism.

To operate the walking toy, the spring motor is wound up by the key 8 and the figure placed in upright position upon the foot members. The spring motor actuating the rotary wing or paddle 10, alternately engages the pallets upon the rocking frame

12, 14, 15, causing said frame to oscillate laterally in a vertical transverse plane, with the result that the limiting impact shoulders 24 will strike a jolting blow upon the body member at the completion of each lateral stroke. As each movement of the rocking frame is completed, the weight 21 is thrown by its momentum slightly to the rear because of the resiliency of the spring blade or arm 19. As the weighted frame reaches the limit of its movement to one side, the figure sways slightly sidewise and turns slightly to the rear upon pivots 35 and 46 of one leg—the left leg, for instance—and thereby lifts the other leg—the right leg—and its supporting foot from the ground to permit the lifted right leg to gravitate forwardly upon hinge 34 to take a step; and to turn slightly on pivot 35 under the action of spring 42 and cam 44. When the right foot is thus lifted, the spring 51, (being under tension from the described slight rearward turn on pivot rod 46), returns the foot member to normal position upon the leg member. In this initial movement, the whole figure turns slightly on the pivotal axis 35 of the left leg joint that is at the moment acting as the support and fulcrum, and at the same time the swaying rearward turning action of the body, also turns the left or fulcrum leg upon its supporting foot and inclines the body slightly forward on hinge 34 of the fulcrum foot.

At the completion of this movement from the first lateral stroke of the rocking weighted frame, the spring motor moves said rocking frame to its opposite position, thereby imparting a jolting blow upon the other side of the body and causing the body to fulcrum upon the right leg and foot which had just previously moved forward for a step. This action causes a repetition of the described movements, the body being first swayed over upon the advanced right leg to lift the left leg for a step forward, the spring 51 returning the foot 45 to normal position upon the left leg when the weight of the figure is removed therefrom, and the left leg gravitating forwardly for a step, as the body sways laterally and turns rearwardly upon the double joint 34, 35 of fulcrum right leg. In this body turning movement, the snap of the weight upon its supporting spring or arm 19 tends to turn the body by the momentum of the weight, and this turning action is also assisted by the slight downward motion of the body member 1 upon the cam edge 44 of the arm 39 of the leg then acting as the fulcrum.

It will be understood that the motion of the leg members upon hinges 34 can be made more or less by adjusting the spring wire 42 in the notches of the arm 39, since the intersection of the spring wires 42 with the slots 40 arrests the motion of the leg members upon their horizontal hinge supports.

My present invention has been illustrated as applied to a form of mechanical walking figure having motor driven means upon the body member for imparting a to and fro lateral swaying motion thereto in combination with transversely pivoted leg members adapted to alternately advance solely by gravity when lifted by the swaying motion of the body member; but I would have it understood that I make no claim to such a construction having gravity operated legs, and that my invention is not limited to a toy having gravitating leg members, but is applicable to other forms of mechanical walking toys irrespective of the force that causes the leg members to move with respect to the body members.

I claim:

1. In a walking figure, the combination with a body member, and leg members having vertical and transverse axial joints connecting them with said body member for relative movement in two planes thereon, said leg members supporting said body member in equilibrium, and actuating mechanism mounted upon said body member adapted to impart a to and fro lateral and backwardly turning swaying motion to said figure to effect the alternate advance of said leg members as in walking.

2. A walking figure comprising a body member, leg members pivotally connected with said body member and supporting it in substantial equilibrium, a laterally oscillating motor driven member mounted upon said body member, and a weight resiliently mounted upon said laterally oscillating member.

3. A walking figure comprising a body member, leg members having jointed connection with said body member and supporting it in substantial equilibrium, a laterally oscillating motor driven member mounted upon said body member, impact stops upon the body member against which said oscillating member strikes, and a weight mounted upon said laterally oscillating member.

4. A walking figure comprising a body member, leg members having jointed connection with said body member and supporting it in substantial equilibrium, a laterally oscillating motor driven member mounted upon said body member, impact stops upon the body member against which said oscillating member strikes, a spring arm carried by said oscillating member, and a weight mounted upon said spring arm.

5. A walking figure comprising a body member, leg members jointed to said body member and supporting it in substantial equilibrium, a spring motor mounted upon said body member, an upwardly projecting oscillating member driven by said motor, a spring arm mounted upon and projecting horizontally from said oscillating member, and a weight mounted upon said spring arm.

6. In a walking figure, the combination with a body member, and a motor driven oscillating weight mounted upon said body member to effect a to and fro swaying motion of said figure, of leg members supporting said body member and having vertical and horizontal axial joints thereon, and means limiting the relative movements between the body member and the leg members.

7. In a walking figure, the combination with a body member, and body-supporting leg members having vertical and transverse axial jointed connections with said body member, said jointed connections providing relative movements in two planes, of motor driven means mounted upon said body member for imparting a to and fro backwardly turning and laterally swaying motion to said figure to effect the alternate advance of said leg members as in walking.

8. In a walking figure, the combination with a body member, and a motor driven oscillating weight mounted upon said body member to effect a to and fro swaying motion of said figure, of leg members jointed to and supporting said body member and arms projecting from said leg members in rear of their body connecting joints, said arms having restricted movable engagement with said body member, and cams between said arms and said body member for turning said body member upon its jointed connections with said leg members.

9. In a walking figure, the combination with a body member, and motor driven means mounted upon said body member to effect a to and fro swaying motion of said figure, of leg members jointed to and supporting said body member, arms projecting from said leg members in engagement with said body member, cams between said arms and said body member for relatively turning said body member and said leg members upon said jointed leg connections, and springs acting upon said arms to yieldingly hold said cams in engagement with said body member.

10. In a walking figure, the combination with a body member, supporting leg members jointed to said body member, and motor driven means upon said body member for swaying and axially turning said body member, of foot members vertically pivoted upon said leg members, and springs arranged between said foot members and said leg members.

11. In a walking figure, the combination with a body member, supporting leg members jointed to said body member by pivotal axes extending longitudinally and transversely of said body member, and motor driven means upon said body member for swaying and axially turning said body member, of foot members vertically pivoted upon said leg members, means limiting the move-

ments of said foot members upon said leg members, and springs arranged between said foot members and said leg members.

12. In a walking figure, the combination with a body member, supporting leg members jointed to said body member, foot members pivoted vertically upon said leg members, springs yieldingly maintaining the normal relation of said foot members and said leg members, coating lugs and notches upon said foot members and said leg members for limiting relative movement between said members, and means upon said body member to impart a to and fro swaying turning motion to said figure.
